UNITED STATES PATENT OFFICE

117,690

DESIGN FOR A RADIO CABINET

Walter Park Gray, Cincinnati, Ohio, assignor to
The Crosley Corporation, Cincinnati, Ohio, a
corporation of Ohio

Application March 6, 1939, Serial No. 83,369

Term of patent 7 years

To all whom it may concern:

Be it known that I, Walter Park Gray, a citizen
of the United States and a resident of Cincinnati,
in the county of Hamilton and State of Ohio,
have invented a new, original, and ornamental
Design for a Radio Cabinet, of which the fol-
lowing is a specification, reference being had to
the accompanying drawing, forming part thereof.

In the drawing:

Figure 1 shows my novel design for a radio
cabinet in front elevation.

Figure 2 is a cross sectional view taken along
the lines 2—2 of Fig. 1.

Figure 3 is a fragmentary cross sectional view
taken along the lines 3—3 of Figure 1.

Figure 4 is a cross sectional view taken along
the lines 4—4 of Figure 1.

Figure 5 is a side elevation of the cabinet drawn
to a somewhat reduced scale.

I claim:

The ornamental design for a radio cabinet,
substantially as shown.

WALTER PARK GRAY.
